UNITED STATES PATENT OFFICE.

SAMUEL R. MUNSON, OF NEW BRITAIN, CONNECTICUT, ASSIGNOR TO
LANDERS, FRARY & CLARK, OF SAME PLACE.

DESIGN FOR AN EGG-BEATER FRAME.

SPECIFICATION forming part of Design No. 32,028, dated December 26, 1899.

Application filed November 9, 1899. Serial No. 736,433. Term of patent 14 years.

To all whom it may concern:

Be it known that I, SAMUEL R. MUNSON, a citizen of the United States, residing in New Britain, in the county of Hartford and State 5 of Connecticut, have invented and produced a new and original Design for an Egg-Beater Frame, of which the following is a specification, reference being had to the accompanying drawings, in which—

- 10 Figure 1 is a front elevation of an egg-beater frame, showing my new design, the lower portion thereof being shown in central vertical section. Fig. 2 is a side elevation of the same, and Fig. 3 is a sectional plan of the 15 lower portion of the said frame on the line xx of Fig. 2.

As shown in the drawings, the frame has a plate-like form, thin in front elevation or edge view and made wider in side view. The upper end of the plate is doubled upon itself into the form of an oval figure A, but with the middle portion curved, as at 4, at the junction of the oval A and body 5 of the frame. Above and below the middle portion of the upright

body 5 there is an offset 6 with straight intermediate portion 7, the portion of the body 5 that is below the offsets 6 6 being, as seen in edge view, in alinement with that portion which is above the said offsets. At the extreme base there is a circular-shaped piece 8, 30 slightly concave on its under side. Near the bottom of the frame, as seen in side view, there is an oval-shaped figure B with double curves 9 9 in the middle portion at the junction of the said oval and body, the metal 35 forming this bottom oval B being of about half the width of the metal in the upright body above said oval, as shown.

Having described my invention, what I claim as new, and desire to secure by Letters 40 Patent, is—

The design for an egg-beater frame, as herein shown and described.

SAMUEL R. MUNSON.
